UNITED STATES PATENT OFFICE.

HORACE O. KELLOGG, OF BOSTON, MASSACHUSETTS.

SHEAR-MOTION CONFECTIONER'S MOLDER OR PRINTER.

SPECIFICATION forming part of Letters Patent No. 699,687, dated May 13, 1902.

Application filed June 15, 1901. Serial No. 64,767. (No model.)

To all whom it may concern:

Be it known that I, HORACE O. KELLOGG, a citizen of the United States, residing at Boston, in the county of Suffolk and State of Massachusetts, have invented a new and useful Improvement in Shear-Motion Confectioners' Molders or Printers, of which the following is a full, clear, and exact description, reference being had to the accompanying drawings, forming a part of this specification, in explaining its nature.

Various kinds of confectionery are shaped and ornamented in molds formed in material like powdered starch. This material is held in a box, the molds impressed in its upper surface by dies, and the confectionery in a fluid state poured into the molds.

The purpose of this invention is to provide a simple operative device for forming these molds; and the invention consists in a frame having a support for the mold-box and an attached vertically-moving hand-operated lever, which carries the dies for forming the molds upon its under surface in inverted position, has a vibrator for vibrating the dies, is moved downward by hand to make the impressions, and is automatically returned to its highest position and held normally in such position.

The invention further comprises means for the adjustment of the die-holder upon the lever and for securing the die-holder to the lever.

In the drawings, Figure 1 is a view in plan of the machine. Fig. 2 is a view in plan of the mold-box in the machine with the die or former board and operating-lever removed. Fig. 3 is a view in vertical section upon the dotted line 3 3 of Fig. 1. Fig. 4 is a view in cross vertical section upon the dotted line 4 4 of Fig. 3.

Referring to the drawings, A is a frame, preferably of wood. It has at its top the cross-supports *a*, upon which the mold-box B rests when in operative position, the box sliding from the front *b* of the frame horizontally into and out of said position. Adjustable stops *b'* limit the extent of its backward movement, and a side rail *a'* and a laterally-adjustable guide *a''* limit the crosswise movement of the box. The end stops and the side guides also permit the employment of mold-boxes

varying in size. The mold-box is filled with powdered starch *b''* or other formative material. Below the mold-box is a pan C, slideable from the front of the frame upon the supports *c* into and out of position. Its office is to receive any material which may drop from the mold-box.

D is the lever for holding the dies or formers *d* and for moving them vertically with respect to the mold-box B and the material therein. This lever is pivoted at *d'* at or near the rear upper corners of the frame and extends forward over the mold-box and has at its front end a handle *d''*, by means of which it is moved downward. Its normal inoperative position is represented by dotted lines in Fig. 3. The position represented by full lines in said figure is that which it and the dies or formers occupy at the end of their downward movement into the material in the mold-box. The lever is formed to permit the placing and removal of the die-board *d''*, the side bars *d''* of the lever having grooves *d''''*, which receive tongues *d''''* on the side edges of the die-board, and the lever is further so shaped that the die-board may be placed and removed from the front of the machine without interference with the handle *d''*. The die-board holder in the nature of bars *d''* of the lever are adjustable with respect to the side arms *d''* of the lever to permit of the vertical adjustment of the die-board. This is accomplished by mounting the bars *d''* upon the lever-arms *d''* and by connecting them with the arms by means of an adjustable connection which will permit the vertical movement of the bars with respect to the arms. I have represented for accomplishing this purpose bolts *d''''*, carried by the bars *d''*, which extend through vertical slots *d''''* in extensions of the arms *d''* and which bolts are adapted to receive nuts which lock them and the bars to the arms. By loosening the nuts the bars may be adjusted upon the arms of the levers to any required extent, thereby adjusting the position of the die-board. In making the adjustment the nuts are loosened, the die-board closes upon the mold-box, and the nuts then tightened to lock the bars to the lever. It will thus be seen that the lever has a holder for the die-board which is adapted to removably hold the die-board and is also adapted

to be adjusted vertically without inclining it unless desired.

The die-board is locked to the lever by means of locking-pins d^{10} , which extend 5 through holes in the side arms into holes in the tongues of the die-board.

E represents strikers which are operated to jar the die-board and dies. They are mounted, as represented in Figs. 1 and 3, at the inner end of the spring-arms e, and these arms extend backward from a common shaft e', mounted upon the lever-arms d⁷. A spring e² is secured to the shaft and one arm of the lever to impel the strikers against the die-board, 15 and a handle e³ extends from the shaft to a position near the lever-handle d², whereby the hand which moves the said handle d² may also move downward the handle e³, and thus lift the strikers. The release of the handle 20 e³ permits the spring to move the strikers with any desired stress against the holder of the die-board, and this release generally takes place at the end of the impressing movement of the dies or formers.

25 In operation mold-boxes filled with the mold-forming material are fed in successive order by sliding from the front of the machine upon their support. As each one is placed in position the lever is moved downward by 30 hand and the dies or formers which it supports are forced into the material in the box and at the same time the dies or formers are jarred by a release of the strikers. The hand is then removed and the lever and dies or 35 formers are automatically moved upward by the spring D', which is expanded by the downward movement of the lever, and this spring also serves to hold the lever and dies or formers in their highest position and removed from 40 interference with the mold-box.

It will be seen that the shear movement of the dies or formers with respect to the mold-box embeds the dies or formers into the starch in a peculiar way, in that those which are at 45 the rear of the board strike the starch slightly in advance of those which are in front of it and the release of the dies from the formed molds is the reverse of this action. This accomplishes two advantages, one of which is 50 especially important. It enables a lighter pressure to be employed, because the compression action is in the nature of a gradual and an advancing one rather than an instantaneous one, and it also permits the dies to be 55 removed from the molds without injuring them, because the movement of each die from its mold has something of a tipping motion, whereby one edge is freed slightly in advance of the other, thereby allowing the air to enter 60 the mold and doing away with the suction which is inherent upon a straight movement of the die from the mold.

Having thus fully described my invention, I claim and desire to secure by Letters Patent 65 of the United States—

1. In a machine of the character specified, the combination of a mold-box for holding

formative material, a lever, a die-board carried by the lever having dies or formers, and means for vertically adjusting the die-board 70 upon the lever without changing its inclination.

2. In a machine of the character specified, the combination of a frame having a support at its top for a mold-box upon which the mold-box may be slid from the front of the machine, adjustable means for centering the box upon 75 said support, a lever pivoted to the frame of the machine, movable upward automatically and downward by hand, a die-board holder 80 carried by the levers and adjustably attached thereto without varying its inclination and also having means for permitting the placing and removal of the die-board.

3. The combination in a machine of the 85 character specified of a support for a mold-box, a means for holding dies or formers and moving them vertically by hand and one or more vibrators, also hand-actuated, during 90 the movement of the lever.

4. The combination in a machine of the character specified of a frame, a movable mold-box supported by the frame, a lever pivoted to the frame, moved upward automatically and automatically held in elevated position, an adjustable die-board holder mounted 95 on the lever, and a removable die-board carried by said holder.

5. The combination in a machine of the kind described of a lever having two side arms 100 and a connecting-handle at their free ends, an adjustable holder comprising two bars having means for carrying a die-board, one of which is mounted upon one of the lever-arms and the other upon the other, and means for 105 adjusting the bars upon the arms.

6. The combination in a machine of the character specified of the lever-arms, the holder-bars mounted thereon and connected therewith by means of slotted connections 110 and coupling bolts and nuts.

7. The combination in a machine of the character described of the lever, its operating-handle, the strikers moved in one direction by hand and in a reverse direction by a 115 spring, the die-board holders mounted upon the lever, and the die-board.

8. In a machine of the character specified, the combination of a frame, a mold-box for holding formative material supported on the 120 frame, a lever attached at one end to the frame extending over the mold-box and having a shear motion relatively thereto, and a die-board carrying dies or formers mounted upon said lever above said mold-box and 125 movable by said lever toward and from said box.

9. In a machine of the character specified, the combination of a frame, a mold-box for holding formative material mounted upon the 130 frame, a lever attached to the frame and extending over the mold-box and having a shear motion relatively thereto, a die-board carrying dies or formers mounted upon said le-

ver and movable thereby toward and from said box, and means for automatically moving said lever and said die-board upward automatically, and for holding them removed 5 from the mold-box.

10. In a press of the character specified, the combination of a mold-box holding formative material and dies or formers mounted upon a lever having a shear motion with respect to

the box whereby the molds are progressively 10 formed by the dies and released from the dies and displacement of the material upon the parting of the dies from the molds due to suction avoided.
